(57) **CLAIM**

The ornamental design for a head for vacuum cleaner, as shown and described.

DESCRIPTION

FIG. 1 is a front perspective view of a head for vacuum cleaner, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is another side view thereof in an alternate configuration; and,

FIG. 10 is another side view thereof in an environment of use.

The broken lines are for illustrative purposes only and form no part of the claimed design.
